UNITED STATES PATENT OFFICE

ANDREW OLSON, OF CLEVELAND, OHIO, ASSIGNOR TO THE CLEVELAND FOLDING MACHINE COMPANY, OF CLEVELAND, OHIO, A CORPORATION OF OHIO

SLIDING DEFLECTOR

Application filed January 23, 1930. Serial No. 422,693.

This invention relates to sliding deflectors for use upon fold plates of buckle type folding machines.

The fold sections of a buckle type folding machine frequently comprise several fold plates, the paper travelling into each of these plates in succession where the maximum number of folds in parallel are to be imparted to the paper. Often times, however, the job in hand requires less than the maximum number of folds, and it is then necessary to disable one or more of the fold plates. This disabling is effected by covering the nose of the plate with a deflector which directs the paper away from that fold plate and into the next succeeding pair of folding rolls. These deflectors are ordinarily hinged to the fold plates and are merely swung from operative to inoperative position or vice versa. The hinged deflector plate is quite satisfactory where plenty of space is available for it to swing about its pivots. The necessity for the provision of this space in some cases however is a determining factor as to the spacing of the fold plate away from a feed table or other associated part, preventing as compact a machine as would otherwise be possible.

One of the objects of my invention is the provision of a mounting for deflectors of this type such that the fold plate upon which it is used may be positioned close to some adjacent part of the machine.

Another object is the provision of a mounting for deflectors wherein the deflector moves forward and backward over the surface of the plate instead of swinging thereupon.

Another object is the provision of a mounting of this character wherein stops may be employed to prevent accidental movement of the deflector in its operative or inoperative position and the deflector may be disengaged from the stops by a rocking movement.

Still another object is the provision of pin and slot connections which accomplish the purposes stated.

Other objects and features of novelty will appear as I proceed with the description of that embodiment of the invention which, for the purposes of the present application, I

have illustrated in the accompanying drawings, in which

Figure 1 is a longitudinal vertical sectional view taken substantially on the line 1—1 of Fig. 2, illustrating a portion of a folding machine embodying my invention. 55

Fig. 2 is a plan view of the same, partly in section upon the line 2—2 of Fig. 1, and

Figs. 3 and 4 are detail sectional views on a larger scale illustrating the deflector and its fold plate in the operative and inoperative position of the latter, these sections being taken substantially on the line 3—3 of Fig. 2. 60

In the drawings the frame of a folding machine is illustrated generally at 10. A feed table is shown at 11 from which sheets are adapted to be directed over a roll 12 and between guide plates 13 and 14 into a fold section. This fold section comprises folding rolls 15, 16, 17, 18, 19 and 20. It also comprises fold plates 21, 22, 23 and 24, the course of paper through the fold plates being in the order named, assuming that four folds are to be imparted to the paper sheets. The rolls 12, 15, 16, 17, 18, 19 and 20 are positively driven by any suitable means. In the present instance I have illustrated a pulley 25 driven by a belt 26 from an electric or other motor, not shown. The pulley 25 is mounted upon shaft 27 which carries a gear 28, the latter meshing with idlers 29 and 30. Idler 29 meshes with a gear fast upon roll 12, and idler 30 meshes with a gear fast upon roll 16, and all of the rolls 15, 16, 17, 18, 19 and 20 are intergeared to travel at uniform speed. 70 75 80

The fold plates 21, 23 and 24 are each provided with a deflector bar 31 that is secured at its ends to arms 32, the latter being pivotally mounted upon aligned studs 33 which are threaded into bosses 34 protruding from the upper surfaces of the respective fold plates. In the drawings these deflectors are shown thrown back into their inoperative positions upon the upper surfaces of the plates, the plates being in their forward or folding position. 90 95

In the case of the fold plate 22, the feed table 11 is located so closely above it that there would be insufficient space for the use of a deflector bar 31 having pivoted arms 32. 100

In this location therefore I employ my present invention, wherein the deflector slides over the top surface of the fold plate. Near the sides of the fold plate a short distance beyond the nose thereof, I form two bosses 35 into which are threaded aligned studs or pivot pins 36, similar to the studs 33 previously mentioned. Slidably and pivotally mounted upon these pins 36 are slotted arms 37 which are secured at their forward ends to the extremities of a deflector bar 38.

In its inoperative position the bar 38 engages behind two small pins 39 protruding upwardly from the fold plate 22, the forward end of the slot in each of the arms 37 at this time engaging the pins 36, so that movement in either direction is prevented. When the deflector bar 38 is in its operative position, illustrated in Fig. 4, a shoulder 40 at the bottom of each arm 37 engages the front edge of a laterally projecting block 41 on the fold plate.

Each of the fold plates 21, 22, 23 and 24 has parallel runners 42 at its side edges which ride upon rails 43 of angle bar form, the vertical flanges of these rails being bolted or otherwise secured to the frame 10 of the machine. The fold plates are thus slideable toward and from the fold rolls. Their movement inward is limited by the engagement of the forward ends of the runners 42 with stops 44 on the frame, as illustrated in Fig. 2. These stops come into use only when the deflectors are in their retracted or inoperative positions. When the deflectors are in their forward or operative positions the movement of the fold plates forward upon their rails 43 is limited by the engagement of the arms 32 or the arms 37, as the case may be, with stop pins 45 also mounted upon the machine frame.

Assuming that the parts are in the position illustrated in Figs. 1, 2 and 3 of the drawings, the fold plate 22 being in the position for imparting a fold, and assuming that the operator desires to disable this fold plate, he first grasps the fold plate and slides it backward upon the supporting and guiding rails 43 until the fold rolls 16 and 18 have been cleared. He then pushes downwardly upon the arms 37 or upwardly upon the deflector bar 38 in order to tilt the deflector upon the pins 36 sufficiently to lift its forward end over the tops of the stop pins 39. The deflector is then slid forward until the shoulders 40 on the arms 37 drop down in front of the forward edge of the blocks 41. At this time the deflector bar 38 has travelled forwardly far enough to clear the nose of the fold plate, so that it is free to descend in front of the latter and cover the intake slot of the plate. In this position of the deflector it is held from movement in either direction, that is to say the engagement of the pins 36 with the rear ends of the arm slots prevents for-

ward motion, and the engagement of the shoulders 40 with the forward edges of the blocks 41 prevents rearward movement. The fold plate is now slid forward until the forward ends of the slotted arms 37 engage the stop pins 45, when the deflectors are in proper position with respect to the rails 16, 17 and 18 to direct sheets of paper passing between rolls 16 and 17 through a curved path into rolls 17 and 18. This position of the parts is illustrated in Fig. 4.

Now when it becomes necessary to again put the fold plate 22 into commission, it is slid back out of the way of the fold rolls, the deflector bar 38 is lifted sufficiently to clear the nose of the plate, causing the shoulders 40 on the arms to clear the blocks 41, after which the deflector may be slid rearwardly. In case the bar strikes upon the forward side of the stop pins 39, a slight tilting of the deflector upon its pins 36 serves to clear this obstacle, and the rearward movement can then be continued. When it has proceeded as far as the pin and slot connection will permit, the operator releases his hold and the deflector bar moves downwardly into position behind the stop pins 39, when it is again held against movement either forwardly or backwardly by the stop pins and the pin and slot connection. The deflector being thus set in inoperative position, the operator slides the fold plate forwardly until the runners 42 strike against the stops 44, as shown in Fig. 2, when the plate is in proper position for the folding operation.

While in the foregoing description and in the accompanying drawings I have disclosed more or less in detail one particular form of the invention, I desire it to be understood that such detail disclosure has been resorted to primarily for the purpose of fully illustrating the invention and is not to be construed as amounting to a limitation upon the scope thereof.

Having thus described my invention, I claim:

1. In combination, a fold plate, a deflector adapted to cover the nose of said plate, and means for mounting said deflector upon said plate to slide forwardly over the upper surface of the plate and to swing downwardly into position in front of the nose thereof.

2. In combination, a fold plate, a deflector adapted to cover the nose of said plate, transversely arranged pivotal means upon said plate, and means for mounting said deflector upon said pivotal means to slide backward and forward thereupon and to swing upward and downward thereupon.

3. In combination, a fold plate, a deflector adapted to cover the nose of said plate, pin and slot means for connecting said deflector with said plate, the pins of said means being arranged in alignment transversely of the plate, said means permitting the travel of

the deflector backward and forward over a surface of the plate and upward and downward around said pins.

4. In combination, a fold plate, a deflector adapted to cover the nose of said plate, a pair of pivot pins mounted near the nose of the plate in transverse alignment, and a pair of arms carried by said deflector, said arms having longitudinal slots into which said pins project, whereby the movement of the deflector forward and backward upon the fold plate and up and down in front of the nose thereof is permitted.

5. In combination, a fold plate, a deflector adapted to cover the nose of said plate, a pair of pivot pins mounted near the nose of the plate in transverse alignment, a pair of arms carried by said deflector, said arms having longitudinal slots into which said pins project, and a stop projecting upwardly from the plate for engagement with said deflector in its inoperative position.

6. In combination, a fold plate, a deflector adapted to cover the nose of said plate, transversely arranged pivotal means upon said plate, means for mounting said deflector upon said pivotal means to slide backward and forward thereupon and to swing upward and downward thereupon, and a stop projecting upwardly from the plate for engagement with said deflector in its inoperative position.

7. In combination, a fold plate, a deflector adapted to cover the nose of said plate, pin and slot means for connecting said deflector with said plate, the pins of said means being arranged in alignment transversely of the plate, said means limiting the forward and rearward travel of the deflector, and stop means adapted to be engaged by the deflector for preventing its rearward movement in the operative position and its forward movement in the inoperative position, said stop means being adapted to be disengaged by the rocking of the deflector upon its pin and slot connections.

In testimony whereof, I hereunto affix my signature.

ANDREW OLSON.
